United States Patent Office

Des. 212,798
Patented Nov. 19, 1968

212,798

TELEPHONE FACILITY DISPLAY MARKER

Henry Dreyfuss, South Pasadena, Calif., and Paul L. Wise,
Indianapolis, Ind., assignors to Bell Telephone Laboratories,
Incorporated, Berkeley Heights, N.J., a corporation
of New York

Filed July 3, 1967, Ser. No. 7,681

Term of patent 14 years

(Cl. D96—12)

FIG. 1

FIG. 2

FIG. 3

FIG. 4

FIG. 1 is a perspective view of a telephone facility display marker showing our new design;

FIG. 2 is a side elevational view of one panel of the display marker shown in FIG. 1;

FIG. 3 is a top view of the display marker shown in FIG. 2; and

FIG. 4 is the marker shown in FIG. 1 illustrating its use with a telephone booth.

The telephones and other structure shown in broken lines are disclosed for illustrative purposes only.

We claim:

The ornamental design for a telephone facility display marker, substantially as shown and described.
